(57) **CLAIM**

I claim the ornamental design for an athletic glove, as shown and described.

DESCRIPTION

FIG. 1 is a front perspective view of a glove;

FIG. 2 is a front elevation view thereof;

FIG. 3 is a back elevation view thereof;

FIG. 4 is a right side view thereof;

FIG. 5 is a left side view thereof;

FIG. 6 is a top plan view thereof; and,

FIG. 7 is a bottom plan view thereof.

The broken lines in FIGS. 1 through 7 show portions of the article and form no part of the claimed design. The stippled areas in FIGS. 1 through 7 indicate a contrast in appearance to the portions without stippling and do not represent any particular material, texture, or finish.
